UNITED STATES PATENT OFFICE.

HENRY KLEIN, OF NEW YORK, N. Y.

STEEL PARTITION AND THE LIKE.

1,241,635.

Specification of Letters Patent.

Patented Oct. 2, 1917.

Application filed December 30, 1913. Serial No. 809,563.

To all whom it may concern:

Be it known that I, HENRY KLEIN, now a citizen of the United States of America, residing at New York city, in the county of

5 New York and State of New York, have invented certain new and useful Improvements in Steel Partitions and the like, of which the following is a specification.

This invention relates to certain improvements in metal partitions and the like; and the objects and nature of the invention will be readily understood by those skilled in the art in the light of the following explanation of the accompanying drawings illustrating 15 what I now believe to be the preferred embodiments and mechanical expressions from among other formations, arrangements and constructions within the spirit and scope of the invention.

20 The invention consists in certain novel features in construction and in combinations as more fully and particularly set forth hereinafter.

Referring to the accompanying drawings:

Figure 1, shows a length of partition embodying my invention and comprising several pilaster posts provided with extensions, several panel units or sections (in this instance, I show sections of different widths) and several partition extension sections arranged between the post extensions.

Fig. 2, is a vertical section on the line 2—2, Fig. 1.

35 Fig. 3, is a vertical section on the line 3—3, Fig. 1.

Fig. 4, is a horizontal section on the line 4—4, Fig. 1.

Fig. 5, is a horizontal section on the line 40 5—5, Fig. 1.

Fig. 6, is a horizontal section on the line 6—6, Fig. 1.

Fig. 7, is a horizontal section on the line 7—7, Fig. 1.

45 Fig. 8, is a detail detached perspective of one end of the chair rail of a section showing how the ends thereof are notched to straddle the stiles of the section and squarely abut the longitudinal shoulders of 50 said stiles.

Fig. 9, is a detail perspective of a post or

pilaster section or unit, showing the bottom support and fastening therefor, and a portion of a post extension and its adjustable end.

55

Fig. 10, is a horizontal section through a corner formation and adjacent posts, and parts of panel sections.

Fig. 11, is a detail perspective view of the upper end of a pilaster post, a coupling iron 60 elevated therefrom, and the upper ends of two stiles separated from the panel sections of which they form a permanent part.

Fig. 12, is a horizontal section in the plane of the line 12—12, Fig. 1, but showing certain parts of the panel section separated.

Fig. 13, is a detail perspective view of a panel section or unit.

Fig. 14, is a vertical section on the line 14—14, Fig. 1.

70

Fig. 15, is a longitudinal vertical section through a portion of the partition.

Fig. 16, is a detail perspective of a portion of the adjustable frame transom or panel frame over the door.

75

Fig. 17, is a horizontal section on the line 17—17, Fig. 16.

Fig. 18, is a detail perspective showing a coupling iron secured to a post and two panel sections.

80

The partition of this invention is made up of pilaster posts provided with extensions, main panel or filling sections or units to fit the posts and fill in the spaces between the posts, and extension or transom sections 85 to fill in the spaces between the post extensions.

In the particular example illustrated, the posts are similar and interchangeable, and each is longitudinally hollow and composed 90 of a sheet steel (or other suitable metal) casing or tubular wall 1, and stiffening bars, plates or members 2, extending approximately throughout the length of said tubular casing and secured thereto. The tubular casing 1, extends throughout the length of main or body portion of the post and is composed of one or more sections of suitable sheet metal drawn, bent up or otherwise manipulated to form the casing with 100 the two front and rear or opposite-side pilaster faces 1^a, that constitute exposed or or-

ornamental surfaces of the partition intervening between the panel sections and the two opposite edge portions 1^b formed to receive the edges of the panel sections of the partition. Said opposite edge portions are depressed or offset inwardly to form longitudinal grooves or sockets extending throughout the length of the tubular casing and arranged between the four longitudinal corners of said casing which in this instance constitute ribs or tongues 1^c, to provide said intervening grooves or sockets. In the example illustrated, the two edge sockets of a post are similar and in width each longitudinal socket is almost equal to the thickness of the post between its front and rear ornamental or exposed surfaces 1^a. The vertical or longitudinal metal plates or bars 2, of the posts are arranged in said sockets and form the floors thereof and the sheet metal is secured thereto by rivets, bolts or screws 2^a, or by other suitable means. These stiffening or strengthening bars 2, extend approximately throughout the length of the tubular casing of the post and are preferably arranged at the exterior thereof approximately as shown, so as to be concealed by the panel sections when the partition is set up. A strong stiff metal post is thus provided which can be readily manufactured in standard sizes and kept in stock. The metal sheets can be readily bent or struck up and the stiffening bars can be readily applied thereto to secure and connect the vertical edges of the sheets and to strengthen and stiffen the completed hollow post, or each post can be composed of a single length of tubing, see Fig. 10.

When set up, the posts of a partition preferably rest on and are secured to a flat floor strip 4, secured to the floor in any suitable manner see Fig. 15. The lower ends of the posts rest on the top face of said strip and are secured thereto by angle brackets 5, having their vertical legs engaging and secured to the lower ends of the stiffening plates 2, by suitable screws or the like, and their horizontal legs resting on the floor strip and secured thereto by suitable screws or the like. These securing brackets are arranged in the lower ends of the edge sockets of the post and hence are covered and concealed when the panel sections are set up and fitted in the posts.

Means are provided at the upper ends of the posts for securing the panel sections and posts together and for holding the posts against movement from the desired perpendicular position. For this purpose, I show each post provided with a pair of vertically elongated plates 6, arranged within the post and extending longitudinally thereof for a suitable distance. These plates are arranged at the inner surfaces of the opposite-side walls 1^a, of the tubular casing 65 of the post, and at their upper ends are

formed with oppositely projecting horizontal flanges 7, extending toward each other in the upper end of the tubular casing so that said flanges are arranged between the upper ends of the edge walls 1^b of the post casing. 70 A coupling plate or iron 8, extends across the upper end of the post casing and rests on the top faces of the flanges 7, and is secured to said flanges by screws 9. The plate projects horizontally and in opposite directions from the upper end of the post to extend over the top portions of the two panel sections fitted in the opposite edges of said post, and is formed with vertical perforations to receive bolts or screws 10, 80 by which said plate is secured to said panel sections. The coupling plate is formed with a central or intermediate portion to occupy the upper end of the tubular casing and to rest on the flanges 7, and this intermediate 85 portion is formed with a central vertical opening 11, co-inciding with the space between the adjacent end edges of the flanges 7, and the edge walls of the post casing for the passage of the post extension, as more 90 fully set forth hereinafter. The upper ends of the edge walls of the post casing are reduced or cut away centrally between the tongues or ribs 1^c, (see Figs. 9, 11) so that the coupling plate can set down in the upper end of the post with its top surface approximately flush with the upper end of the post, i. e., with the top edges of the side walls 1^a. The end portions of the coupling plate are reduced in width to fit down in 100 the cut away portions of the edge walls so that the central or intermediate portion of the plate can fit down within the post end and approximately completely fill the same and in connection with the plates 6, lock the 105 post against independent lateral play or movement. The reduction of the coupling plate end portions, forms the body or intermediate portion of the plate with corner stop shoulders 12, to abut the inner surfaces of the corner portions of the edge walls and thereby aid in bracing the post and locking the same to the coupling plate. 110

In Fig. 1, I indicate the panel sections by the reference letters a.

The panel sections are composed of metal and while I prefer to make all of these sections of the same height, also all of the pilaster posts of the same vertical length, yet panel sections can be provided of different widths to suit various requirements. These sections are all of the same construction and hence are interchangeable. In Fig. 1, panel sections of different widths are shown merely for the purpose of indicating that these sections can be made up according to certain standard sizes. The panel sections are individually complete and are preferably made up in quantities at the shop or factory, and this also applies to 130

the posts, and kept in stock so that the necessary units can be selected from stock and at once sent out ready to assemble and be set up at the place where the partition is required.

In the particular example illustrated, each panel section, consists of a pair of similar vertical opposite-longitudinal-edge pieces or stiles 14, a top rail, a chair rail, 10 and a base rail, a glass panel, and an opaque panel. Each stile is of a thickness, from one side face to the other, to snugly fit in the edge socket or groove of any pilaster post unit with its flat parallel side faces 14^c, 15 overlapping the flat parallel inner longitudinal side faces of the pair of longitudinal ribs 1^c, of said post unit forming the side walls of said post socket (see Fig. 11). The side faces 14^c, of the stile are of greater 20 width than the side faces of the ribs 1^c, between which said stile fits (see Fig. 11). The inner longitudinal portion of each stile, beyond the opposite flat side faces 14^c, is of reduced thickness, thereby forming the 25 alined flat parallel opposite side shoulders or abutments 14^d. The longitudinal reduced portion of each stile is formed with a longitudinal groove, socket or depression 14^e, at its longitudinal edge to receive the 30 panel moldings.

The corresponding outer longitudinal edge 14^a, of each stile forms a longitudinal socket or depression between the opposite edge tongues or flanges 14^b. These stiles extend 35 throughout the vertical length of the panel section and at their upper ends are fitted and secured to the ends of the top rail 15, and this top rail 15, is preferably of the same cross sectional dimensions and forma- 40 tion as the said stiles. The ends of the stiles and top rail 15, can if so desired, be cut off angularly and permanently fixed together to form miter joints at the upper corners of the panel section.

45 A stiff reinforcing plate or bar 16, is preferably arranged on and longitudinally of the top edge of the panel section and secured thereto by vertical screws or other means. This bar preferably extends approximately 50 throughout the width of the panel section and fits down in the longitudinal top depression or groove of the top rail of said section between the longitudinal edge flanges of said rail that correspond to the edge flanges 55 14^b, of the stiles 14. The chair and base rails of the section extend between and are fixed to the two stiles, and are vertically and centrally notched at their ends to straddle and snugly fit the longitudinal reduced inner 60 edge portions of the stiles and so that the squarely cut off end edges of each rail end at opposite sides of the notch will squarely abut the opposite shoulders 14^d, of the stile, see Figs. 7, 8, and 13, with the opposite side 65 faces of the rails in part at least approxi-

mately flush with the side faces 14^c, of the stiles.

The vertical notches in the rail ends straddling the reduced longitudinal inner edge portions of the stiles, will accurately 70 center all of the rails so that the rail side faces will be properly located with respect to the stile side faces and will enable the operatives to accurately and easily fit the rails and stiles together, while the provision 75 of the stiles with ledges or shoulders 14^d, against which the ends of the rails squarely abut renders it possible to cut the rails in quantities to exact lengths and to rapidly and accurately assemble the same with and 80 fit the same to the stiles with the formation of finished joints between the stiles and rails and the production of panel sections of accurate widths. A particular object is to provide partition structures whereby the 85 partition units can be individually completed and finished at the factory and kept in stock in quantities ready to be shipped or sent out knocked down, and capable of being assembled and set up in office buildings and 90 elsewhere without the assistance of expensive skilled or expert labor. It is very expensive to send skilled or expert mechanics from the factory to set up and assemble partitions. In fact, it would be impossible to 95 do so from the standpoint of cost where the partition is shipped knocked down to distant cities for erection. However, partitions built in accordance with my invention can be shipped knocked down to distant points and 100 can be there erected by unskilled mechanics without the aid of skilled or expert assistance.

Furthermore, the panel section parts, whether wooden or metal, can be very eco- 105 nomically manufactured and assembled to form the completed finished sections where composed of the stiles and rails approxi- mately as disclosed.

By employing stiles approximately of the 110 cross sectional formation described, I avoid the expense of separate panel frames between the stiles and various rails inasmuch as the reduced inner edge portions of the stiles form the vertical portions of the panel 115 frames, and the various rails can be correspondingly formed to constitute parts of the panel frames. To this end, I form the top rail 15, of the same cross sectional form as the stiles, and hence the inner longitudinal 120 edge portion of said top rail is centrally reduced at its side faces and its inner edge wall is formed with longitudinal groove or socket 15^a. The top and bottom portions 17 of the chair rail are also of approximately 125 the same cross sectional form as the top rail and consequently have the longitudinal reduced edge portions formed at their edge walls with longitudinal grooves or sock- ets 17^a.

The top portion 18 of the base rail is also of approximately the same cross sectional form as the top rail and its reduced edge portion has the longitudinal groove 18^a.

5 Any suitable upper panel, such as glass panel 19, is arranged in the frame formed by the two stiles, the top rail 15, and the upper portion 17 of the chair rail, and this glass panel is secured in molding 20, formed by strips of molding connected at their ends by miter joints or otherwise. These moldings are fitted in the grooves 14^a, of the stiles and 15^a, and 17^a, of the top rail and chair rail. These moldings are formed with a 10 fixed bead, and the glass is secured thereagainst by removable beads or strips 20^a, secured by screws 20^b, passing through moldings 20, and into reinforcing bars 20^c, in said moldings, see Fig. 12, among others.

15 20 Any suitable lower panel, such as opaque panel 21, (metal if so desired) is secured in the frame formed by the stiles, chair rail and base rail by suitable grooved molding 21^a, consisting of strips of molding preferably 25 connected at their ends by miter joints and fitted in and held by the grooves 14^a, of the stiles and the grooves 17^a, and 18^a, of the chair and base rails. The panel is fitted in the groove of the molding before the same 30 is secured and molding frames 20, and 21^a, can be fitted in the panel section before the stiles and rails thereof are permanently secured together.

In the steel or other sheet metal construction illustrated, I form the stiles of similar 35 lengths of the same kind of tubing, in the matter of dimensions and shape. The top rail is also composed of a length of the same tubing.

40 The chair is composed of a main or center length 17^b, of tubing approximately rectangular in cross section and two lengths 17 of the same kind of tubing as the stiles and top rail. The thickness of the center tube 45 17^b, is less than the extreme thickness of the upper and lower tubes 17, of the chair rail and said center tube 17^b is shown fitted between the edge flanges 17^c, of said upper and lower tubes 17, see Fig. 3, whereby the 50 chair rail is stiffened and braced and the chair rail as an entirety presents a paneled effect or pleasing design.

The base is composed of a top section 18, composed of a length of the same tubing as 55 the stiles and certain of the above mentioned cross bars; a usually enlarged or heavy bottom tube 18^b, rectangular in cross section and having opposite edge top longitudinal flanges 18^c; and an intermediate rectangular tube 18^d, fitting between the flanges 18^c, of the lower tube and between the edge flanges 18^c, of the upper tube 18, whereby the base 60 or bottom rail is stiffened and braced, and whereby the base as an entirety presents a 65 paneled effect, see Fig. 3. The base tube

18^b, is formed with a bottom wall to rest on the floor strip 4, when the partition is set up.

The various tubes 17, 17^b, 18, 18^d, and 18^b, are centrally and vertically notched at their ends, as hereinbefore described, to 70 straddle the reduced longitudinal edge portions of the stiles and to produce flat ends squarely abutting the flat shoulders 14^a, of the stiles, see Figs. 7, 8 and 13. The ends of these rail-forming tubes are permanently 75 secured to the stiles by brazing, electric welding or in any other suitable manner.

I attain great economy in sheet metal partition work, as well as a most desirable and advantageous construction, by thus forming 80 the stiles and most of the rails of the panel section of lengths of the same tubing. The dies employed in making sheet metal tubing or casings are very expensive, and it is expensive to form tubes of different sizes 85 and shapes.

I reduce to a minimum the number of different dies and operations required by thus using a maximum number of parts composed 90 of lengths of the same size and form, and at the same time I am enabled to produce completed finished panel sections of a superior and highly advantageous construction.

The partition is provided with a suitable 95 cornice arranged longitudinally thereof preferably so as to extend upwardly from the upper ends of the panel sections and the pilaster posts, and bridging or continuous across the joints between the post and panel 100 section units. In the particular example illustrated, this cornice is formed by pairs of long strips of parallel moldings 22, of any suitable design pressed up from sheet metal and extending upwardly and laterally 105 in opposite directions from the upper ends of the post and panel section units. The lower longitudinal edge portion of each molding, is formed with a horizontal longitudinal flange 22^a, projecting inwardly 110 or laterally from a longitudinal depending rib or shoulder 22^b. These flanges of the moldings rest longitudinally on the upper faces of the reinforcing bars 16, of the panel section top rails and on the 115 coupling bars 8 and are removably bolted or otherwise secured thereto by the fastenings 22^c, and the two opposite-side moldings diverge upwardly from the upper ends of the panel sections and posts to the desired 120 height.

The coupling bars 8, preferably have threaded sockets in their end portions to receive the crown or cornice molding fastenings, 22^c, and also at the opposite 125 sides of their body or intermediate portions so that crown molding fastenings 22^c, can extend therethrough and into bolt or screw holes in the laterally bent ends 7, of the plates 6. The longitudi- 130

nal depending ribs 22^b, of the crown moldings are designed to traverse the opposite vertical side faces of the upper ends of the pilaster posts (see Fig. 2) and depend below the level of the upper ends of said posts and thereby conceal the joints between the moldings and posts and also center the parts and lock them in alinement.

In the particular example illustrated, I show the top longitudinal edge portions of the diverging crown moldings formed by inwardly projecting horizontal longitudinal flanges 22^d, removably secured together by horizontal plates 23, arranged longitudinally of the cornice and having central longitudinal groove or socket 23^a.

Where a door, such as 24, Fig. 1, is to be provided in the partition, two pilaster post units are fixed the required distance apart and at their upper ends above the door opening, are fixedly connected by the cornice and a panel section reinforcing bar 16, to which the cornice and the coupling plates 8 of said units are fixed.

The two post units constituting the door posts, are provided with removable strips to form the door stop or bead and to receive the hinges carrying the door. For instance, posts can be provided at their edges facing the door opening with sheet metal tubes 25, secured thereto removably by screws or other means and extending throughout the length of each post and at their upper ends secured to the cornice or to the coupling plates 8, if so desired.

Each sheet metal tube 25 can be formed to fit between the corner ribs or tongues 1^c, and to overlap the outer faces thereof (see Fig. 12) and is formed with door stop forming bead or shoulder 25^a. These door stops 25, can be readily applied to the post units and can be readily removed therefrom without damage thereto.

Each pilaster post is preferably provided with a post extension 26, centrally and longitudinally arranged therein and projecting upwardly therefrom through the opening 11, of the coupling plate 8, of such post. The extension bar or member of a post is usually of about the same length as the post and is vertically slideable therein to project the distance above the post required by the partition superstructure or transom sections to be employed in the particular partition being installed. The extensions are slideable or adjustable vertically and are held or secured in the desired vertical adjustment by any suitable means. For instance, when the distance that the extensions must project above the posts or main partition in any particular instance, is determined, holes can be drilled through said extensions at the proper points, and pins 26^a, can be inserted in said holes to project laterally beyond the edges of the extensions and rest on the cou-

pling plates 8, and thereby uphold the extensions projecting the required distance above the main partition.

Each post extension 26, is composed of sheet steel or other metal pressed into tubular form or to form a tubular casing reinforced approximately throughout its length by the longitudinal metal bars 27, to which the sheet metal is suitably secured.

The sheet metal forming the post extension is pressed to provide each edge of the extension with a pair of longitudinal parallel projecting corner ribs or tongues 28, a pair of parallel grooves 28^a, between said ribs, and a fixed bead 29, between said grooves.

The panels (usually glass) 30 of the transoms or superstructure are usually fitted between the edges of the post extensions and against the side faces of the fixed beads 29, thereof and said glass or other panels are secured or clamped against said fixed beads by removable metal strips or beads 31, the same as described in connection with the glass panels 19, of the main partition.

The removable strips or beads 31, are removably secured by machine screws or the like, extending therethrough and through the sheet metal of the tubular casing and into threaded holes provided in the metal reinforcing bars 27.

The glass or other panels 30, of the transom or superstructure, can be confined at their vertical edges to the post extensions, as just described, and at their lower horizontal edges to cross bars or rails 34, and at their upper horizontal edges to upper cross bars or rails 35. The lower rails 34, can be pressed up from sheet metal to form tubular casings along their upper edges having fixed beads 34^a, against which the panels are clamped by removable beads 34^b, secured by screws adjustably and removably entering threaded holes in reinforcing bars 34^c, fixed in the sheet metal tubes or casings. The upper rails 35, are also formed by hollow sheet metal casings having fixed and removable beads between which the panel 30, is clamped as just described in connection with the lower rail 34. The upper rails 35 are stiffened and braced by upper channel bars 35^a, arranged longitudinally thereof and secured between the upper longitudinal edges of the sheet metal casings forming said rails.

The ends of the rails 34, 35, are centrally notched vertically to transversely fit and straddle the beads 29, 31, of the post extensions 26, and to form the pairs of longitudinally-projecting parallel tongues or flanges 36, arranged at the opposite sides of the end and formed to slidably enter the longitudinal grooves or sockets 28^a, in the longitudinal edges of the post extensions. The rails are thus formed by the projections 36, 13^c

and intervening notches, to fit the inner longitudinal flat faces of the ribs 28, to center the rails and hold them against lateral deflection and to conceal the joints between the 5 post extensions and rails even though there are approximately slight inaccuracies in the lengths of the rails or the lateral positions of the post extensions. The side faces of the tongues, flanges or projections 36, of the 10 rails lap the inner vertical faces of the ribs 28, for substantial distances and these distances can be varied before the rail ends separate from the edges of the post extensions, see Figs. 4 and 9.

15 The rails 34, 35, are made in certain lengths and kept in stock, and are removably fitted between the post extensions as the partition is put up, and can be arranged a greater or less distance apart along the 20 post extensions according to the sizes of the panels 30, employed in each instance, as the ends of the rails will removably interlock with the edges of the post extensions at any points throughout the portions of their 25 lengths formed to receive the panel ends. In the completed partition, the removable lower rails 34, of the superstructure rest on and are supported by the plates 23, of the cornice or crown molding of the main partition. These lower rails usually fit in and 30 are arranged longitudinally of the grooves 23^a, of said plates.

35 The partition superstructure or transom portion is provided with a cornice preferably formed by opposite-side moldings 37, pressed up from sheet metal and extending upwardly and outwardly from the opposite sides of the top edge portions of the top rails 35 and secured thereto and also traversing 40 opposite sides of the upper end portions of the post extensions and secured thereto. These moldings are secured to the parts mentioned by machine screws 37^a, or the like, passed removably through the vertical lower 45 longitudinal edge portions of the molding and into the post extensions and into the channel bars 35^a, of the top rails. The screws 37^a, extend through perforations in the sheet metal of said top rails, and enter 50 threaded perforations in the depending flanges of the channel bars. If so desired, the upper portions of the hollow post extensions 26, can be braced and stiffened by comparatively short stiff bars or tubes 40, forming 55 adjustable ends arranged therein and adjustable longitudinally thereof to project the required distance upwardly therefrom. These top bars are particularly useful where the ceiling to which a partition must be extended, has exposed beams (see Fig. 1). Under such circumstances, the upper cornice 37, will approximately close up against the under or bottom edges or faces of the cross beams *b*, but means must be provided to fill 60 65 in the spaces between said cross beams and

from the upper cornice 37 to the ceiling. For this purpose, I usually employ spaced sheets of suitable fire proof material 41, usually fire-proof material strips 43, secured between their lower edges, while the upper 70 ends of the sheets 41, are secured to usually grooved ceiling strip 42, and fit the opposite edges thereof. The ceiling strip is suitably secured to the ceiling. These sheets and strips form removable filling panels at their 75 top edges fitting the ceiling, at their vertical edges fitting the vertical sides of the exposed beams, and at their lower edges fitted between the vertical lower portions of the opposite moldings 37, and usually resting on 80 the channel bars 35^a.

Where a post extension happens to be located beneath an exposed beam *b*, such extension can extend up to the beam and fit the ceiling strip 42, which extends across all the 85 beams and along the ceiling the full length of the partition. Where a post extension is located below the space between such beams, the end bar 40 of such extension is projected upwardly to the ceiling strip 42, and is suitably secured in such position, to brace the parts and stiffen the partition where the post extension itself does not extend to the ceiling, and in the completely finished and assembled partitions, the adjustable ends 40, 90 are concealed between the sheets 41.

By providing the post extensions with such telescoping or adjustable ends, said extensions of a partition can all project the same distance above the main partition, that 100 is, above the posts, and variations in the height of the ceiling can be taken care of by the adjustable ends 40, and by the top edge filling panels 41, whereby certain advantages are attained.

It is desirable to have the post extensions 26 of a partition all project the same distance above the main partition so that the upper cornice moldings can be secured to the upper ends of all said extensions and thus 110 follow a straight horizontal line, and so that the holes in the extensions for the means (such as pins 26^a) upholding said extensions will be located in all extensions a like distance from the upper ends thereof.

Any suitable means or provision can be provided for securing the adjustable ends 40, to the post extensions after being adjusted to the desired positions. For instance, I show certain of the upper-cornice-securing screws 37^a, extended through the cornice and the post extensions, and into threaded holes in the adjustable ends 40, as shown by Fig. 14, thereby constituting a substantial support for said screws and reinforcing the post extensions where the screws pass therethrough. The screw holes can be drilled in the adjustable ends to suit the requirements of each partition.

It is the common practice to provide 130

swing or pivoted sashes or transoms in partitions above doors. Inasmuch as the superstructure of my partition is extensible to accommodate the partition as an entirety 5 to rooms having ceilings of various heights, I provide a vertically extensible or adjustable swinging transom frame to receive a glass panel of any vertical width within certain limits, whereby similar extensible 10 transom frames can be constructed and kept in stock and adapted to partition superstructures of almost any height.

The particular construction of extensible transom frame illustrated by Figs. 1, 16, and 15 17, is rectangular in shape and consists of tubular sheet metal casings forming an open frame adapted to receive a glass panel 46. The tubular frame is formed with a fixed bead 47, against which the glass panel is 20 secured by removable beading 47^a, removable secured by screws entering reinforcing bars 47^b, in the tubular casing approximately as hereinbefore described in connection with other portions of the partition.

25 The tubular sheet metal frame comprises upper and lower rails and vertical stiles. The stiles are fixed to the rails but the stiles are composed of slidably telescoping sections. For instance, the upper rail 48, is 30 fixed to a pair of depending stile sections 48^a, while the lower rail 48^b, is fixed to a pair of upwardly extending stile sections 48^c, slightly larger than the sections 48^a, and slidably receiving the same so that the frame 35 as whole can be increased or diminished in vertical length to receive a glass panel of the required size by moving the rails toward and from each other and thereby sliding the stile sections one within the other to decrease 40 or increase the length of the stiles. Suitable set screws 48^d, can be provided to secure the stiles in the desired adjustments, and if so desired, reinforcing channel irons 48^e, can be arranged within the overlapping portions 45 of the stile sections. If so desired strips of felt can be arranged between the glass panel and the fixed beads 47, to make up for inequalities due to the overlapping sections.

50 The upper and lower rails 48, 48^b, can be provided with central vertical pivots 49, on which the transom is horizontally swingable (see Fig. 1) and these pivots can be mounted in upper and lower transom supporting 55 bars 50, 51, extending between a pair of post extensions 26, and suitably secured in the partition approximately in the horizontal lines of the superstructure rails 34, 35, respectively.

60 Wherever it is necessary for the partition to change its direction and thereby form a corner, I provide an improved corner post, or angular or corner formation, by fixing a pair of post units adjacent to the apex of 65 the angle of the corner or turn and filling

in the space between the two posts by a corner or angular section or unit extending from the floor strip to the corner molding or cornice and another similar superstructure section extending from the crown molding to the upper cornice, while the space above the upper cornice can be filled in by the panels 41. This corner section consists of a double angular panel formed by spaced metal sheets 53, bent laterally to the required angle and secured to and spaced by interposed strips 54. The vertical edges of the panel are secured to and finished by tubes 14', corresponding exactly to the tubes 14 of the panel sections and fitted removably in 70 the edge grooves of the post units, as shown by Fig. 10.

In setting up a partition, I usually secure the strip 4 to the floor by any suitable means and extend said strip throughout the full 85 length of the partition and from wall to wall. This strip can consist of sheet metal pressed to the required form and preferably backed by and secured to a body of wood covered by the sheet metal. If so desired, 90 vertical metal strips 4^a, can be arranged longitudinally along the opposite edges of the floor strip with their lower edges extending to and usually following the floor surface where the floor is uneven or not level.

The partition usually starts with a pilaster post located adjacent to a wall but spaced a short distance therefrom. The space between the post or end of the partition and said adjacent wall can be filled in by any suitable 100 means. For instance, this space can be filled in by fire proof double wall panels fitting the wall and the adjacent post and consisting of spaced sheets 55, secured to and spaced by strips 56, and at one vertical edge secured or fitted in vertical sheet metal tubes 14'', that snugly fit in the edge groove of the adjacent post unit and that approximately correspond in action to the tubes 14 of the panel sections.

110 The corresponding filling panel between the post extension and the wall, can have the edges 55', of its sheets 55, extended to fit in the longitudinal edge grooves 28^a, of the post extensions see Fig. 4.

Finishing strips 57, can be provided, corresponding to the strips 4^a, of the floor strip, to conceal spaces between the edge of the panels and the wall. The crown moldings or cornice 22, and the upper cornice 37 are 120 usually extended from the adjacent post and its extension to the wall, see Fig. 1.

The cornice moldings 22 are in long lengths so as to be continuous from post to panel section units approximately throughout the length of the top of the main partition and constitute an important reinforcement for the partition rendering the same (in connection with the coupling plates 8) exceedingly stiff and rigid against lateral strains. 125 130

The upper or superstructure cornice moldings 37 are also provided in long lengths approximately continuous throughout the partition and are secured to the post extensions and 5 rails 35, and render the superstructure exceedingly strong and stiff against lateral strains and thereby brace and stiffen the main partition.

The posts with their extensions and adjustable ends are preferably alike and are made up in quantities and kept in stock.

The panel sections of the main partition are also standardized and made up in quantities completely finished and kept in stock 15 so that any panel section is adapted to any post. The moldings, couplings and transoms are also preferably standardized and kept in stock.

These various parts making up a partition 20 can be readily assembled and set up to constitute a complete partition, and can also be readily separated without damage or injury to render the partitions readily removable and subject to alteration and remodeling 25 without destroying the usefulness of the various sections or units in other partitions, or in different portions of the same partition.

The panel sections can be made up complete in various standard widths.

30 In setting up a partition, the first pilaster post is mounted on the floor strip and secured in position by a bracket 5, or other suitable means. A panel section is then placed in position on the floor strip and 35 snugly fitted to the post with a longitudinal stile 14, of the section properly entered in a longitudinal edge socket of the post between a pair of corner ribs 1^c, thereof. The next post is then set up and secured by a 40 bracket 5, with the other stile 14, of said panel section fitted snugly between the adjacent ribs 1^c, 1^c, of said last mentioned post. The posts and panel sections are thus secured and assembled to complete the main 45 partition.

Then before the cornice 22, of the main partition is applied and secured thereto, the upper ends of the various posts and sections are coupled together by the coupling 50 plates 8.

Each coupling plate, having a pair of depending plates 6, secured thereto, is dropped into the upper end of its post so that the plates 6, depend in the post as hereinbefore 55 described, and the ends of the plate 8, overlap the top rails of the two panel sections fitting said post. These plate ends are then secured to said top rails by screws or bolts as hereinbefore described. Each post is 60 coupled to the panel sections fitting it, by these coupling plates as just described.

The various post extensions can then be drawn up out of their posts to project the required distance above the main partition, 65 and the pins 6^a, are applied to uphold the

same. The cornice moldings of the main partition can then be applied and removably secured to the top rails of the panel sections and to the coupling plates 8, as hereinbefore described.

The superstructure, panels and transoms can then be removably fitted between the post extensions and their adjustable ends and the upper or superstructure cornice can be applied, all as hereinbefore described, 75 to complete the partition.

Peculiar advantages are attained by providing complete panel sections or units with the longitudinal parallel projecting flat edge stiles 14, to fit snugly between the edge or 80 corner ribs of the posts, and overlap the inner side flat vertical faces of said ribs for considerable distances and in sliding engagement. This formation not only causes the panel sections and posts to snugly interlock against independent lateral play, but the joints between said parts are concealed and comparatively extensive movements of parts in the line of the partition will be required to cause a post and panel section to 85 separate so far as to withdraw the stiles 14, from the inner side faces of ribs 1^c.

It is evident that various changes, modifications, and variations might be resorted to, that parts might be added and that features might be omitted without departing from the spirit and scope of my invention, and hence I do not wish to limit myself to the exact disclosure hereof.

What I claim is:—

1. A partition comprising a main partition, and a superstructure secured thereto and rising therefrom and consisting essentially of vertical panels, vertical post-like extension members vertically adjustable with respect to said main partition when being set up, and vertically adjustable ends for said members adapted to be projected upwardly therefrom to the ceiling, substantially as described.

2. A partition comprising a main partition, and a superstructure secured thereto and rising therefrom and consisting essentially of vertical extension members provided with ends, each end being longitudinally adjustable with respect to its member and adapted to be projected upwardly therefrom to the ceiling, means for securing each adjustable end to its member in the desired adjustment, and panel sections for filling in the spaces between the members and upwardly projected ends.

3. A partition provided with a superstructure comprising post-like extensions, panel sections between the same, adjustable 125 ends projecting upwardly from certain of said extensions, filling panels between said ends, a cornice traversing said extensions and panel sections, and means securing said cornice to said extensions, said means also 130

serving to secure said ends to their respective extensions in the desired vertical adjustment with respect to said extensions.

4. A knock-down partition comprising a main partition, and a superstructure supported thereby and rising from the top edge thereof and consisting essentially of vertical panels, upper and lower rails for said panels, and vertical extension members having longitudinally beaded edges to receive the vertical edges of the panels and also having pairs of longitudinal sockets in said edges, the ends of said upper and lower rails having pairs of longitudinally projecting tongues to removably enter said sockets and intervening vertical recesses to receive said beaded edges whereby said rail ends can be fitted to and interlocked with said extension members at any portions of the lengths of their beaded edges, substantially as described.

5. A partition comprising post-like members having longitudinal edges formed with pairs of longitudinal sockets, said edges between the sockets of each pair being formed to receive and secure panels, and panel holding rails having their end edges formed to fit said member edges between the sockets and provided with pairs of tongues entering said sockets, substantially as described.

6. In a partition, in combination, a main partition, and a superstructure comprising a post-like member composed of a sheet metal tube at opposite longitudinal edges formed with pairs of longitudinal ribs and intermediate fixed longitudinal beads, removable beads to secure panels against said fixed beads, and panel rails having end tongues and recesses to fit between the ribs and to receive said fixed and removable beads, substantially as described.

7. A partition comprising a main partition, and a superstructure supported thereby and rising therefrom and consisting essentially of vertical post-like members extending down into the main partition and having longitudinal edges beaded to receive panels, vertical panels, lower panel rails on the top edge of the main partition and at their end edges vertically recessed to receive and fit said longitudinal edges of said members, top rails for said panels vertically recessed at their end edges to receive and fit said longitudinal edges of said members and interlock therewith against lateral deflection therefrom, and a continuous crown molding extending across and secured to side faces of said members and along and secured to side faces of said top rails and supporting said top rails, substantially as described.

8. A knock down partition comprising panel sections, each section provided with vertical stiles having opposite parallel vertical side faces, the inner vertical longitudi-

nal portions of said stiles being centrally reduced and forming longitudinal shoulders at both side faces and intermediate the widths of the stiles, rails between said stiles having their ends vertically and centrally recessed and receiving said reduced inner portions of the stiles and forming end edges squarely abutting said shoulders, pilaster members intervening between said sections and having longitudinal projecting edges overlapping said parallel side faces of said stiles to form concealed joints between the members and sections, and a crown molding secured to said sections and continuous from section to section across said members.

9. A partition consisting essentially of a main partition, and a knock-down superstructure comprising vertical panels, horizontal rails removably receiving the upper horizontal edges of the panels, vertical stiles receiving the vertical edges of the panels and composed of vertical extension members having their longitudinal edges beaded to their upper ends to receive and secure said panels, said rails having their ends similarly recessed or notched centrally and vertically to removably fit and receive said beaded edges of the extension members at any points along the lengths of said beaded edges and to thereby interlock therewith against lateral deflection therefrom and a removable continuous molding traversing said extension members and arranged longitudinally of and connected to said rails, substantially as described.

10. In combination, in a knock - down sheet metal partition, main partition panel sections spaced apart at their vertical edges, pilaster sections closing the spaces between said panel sections and removably lapping the opposite side faces of the vertical edge portions of said panel sections throughout the vertical lengths thereof, a continuous removable cornice above said pilaster and panel sections and having longitudinal bottom flanges at the top ends of said pilaster sections and removably secured to the top edges of said panel sections, partition superstructure post extensions depending between said panel sections and extending upwardly between the flanges of said cornice, superstructure panels between said extensions above said cornice, and removable bottom rails for said panels at their lower edges fitting down on said cornice and at their ends removably fitting the edges of said extensions.

11. A partition comprising top vertical panel sections provided with top rails, crown moldings arranged along the opposite faces of said rails and projecting upwardly from said rails to form a socket between their vertical portions and above the top edges of said rails, the upper longitudinal edges of said moldings being spaced

apart, and vertical filling panels adapted to close the space between said top rails and the ceiling and fitted down into said socket in engagement with said vertical portions of the crown moldings whereby said panel is held against lateral displacement.

12. In combination, in a sheet steel knock down partition, pilaster post members at their lower ends adapted to be secured to the floor, panel sections between and at their vertical edges interlocking with said members against lateral deflections, coupling plates traversing the upper ends of and confined to said members and extending onto and secured to the top edges of said sections, and a continuous crown molding arranged above said members and sections and having longitudinal bottom flanges fitted down on the top edges of said sections and the top ends of said members and arranged on and removably secured to said plates and continuous across the joints between the members and sections, substantially as described.

13. A knock down partition comprising a longitudinal floor strip, removable pilaster posts at their lower ends removably seated on said strip, said posts having longitudinal sockets throughout their opposite edges, angle brackets removably secured on the floor strip and to the posts, said brackets having their upright arms arranged in sockets of the posts, panel sections removably seated on the strip and at their vertical end edges removably seated in said sockets, said sections concealing said brackets, and means removably securing together the upper ends of the posts and panel sections, substantially as described.

14. A main partition, in combination with a superstructure comprising extension posts approximately throughout the lengths of their opposite edges formed to constitute the uprights of panel frames, removable cross bars extending between said extension posts to form the upper and lower rails of removable filling panels above said main partition and between said extension posts, the opposite edges of said several cross bars being similarly notched vertically to transversely fit the edges of said extension posts at any points along the lengths of said edges thereof against lateral displacement without being secured at their ends to said extension posts.

15. A knock down partition comprising longitudinally-hollow removable pilaster posts, means for removably securing the lower ends thereof to the floor, the opposite edges of said posts formed approximately throughout their lengths with longitudinal seats, removable panel sections at their vertical end edges removably fitted in said seats of the posts approximately throughout the lengths thereof, and removable coupling members traversing the hollow upper ends of the posts and removably secured on the top edges of the panel sections, said coupling members having depending plates rigid therewith and removably fitted in the open upper ends of the posts to center said members with respect to the posts.

In testimony whereof I affix my signature in presence of two witnesses.

HENRY KLEIN.
